UNITED STATES PATENT OFFICE.

CHESTER L. JENSEN AND LONNIE A. LAHEY, OF SPOKANE, WASHINGTON.

CRUTCH.

974,494.

Specification of Letters Patent.

Patented Nov. 1, 1910.

Application filed November 2, 1909. Serial No. 525,902.

To all whom it may concern:

Be it known that we, CHESTER L. JENSEN and LONNIE A. LAHEY, citizens of the United States, residing at Spokane, in the 5 county of Spokane and State of Washington, have invented certain new and useful Improvements in Crutches, of which the following is a specification.

Our invention relates to crutches, the object being to provide a crutch which, while having a resilient armpit support or rest, is resiliently yielding to permit of a proper backward and forward motion of the shoulder of the user, the invention consisting in 10 interposing a spring of peculiar construction between the head and body or staff of the crutch, said spring being so constructed as to yield vertically and to have a motion in the arc of a circle backwardly and forwardly with a minimum of sidewise movement.

For a full understanding of the invention and the merits thereof, and to acquire a knowledge of the details of construction, 15 reference is to be had to the following description and accompanying drawing, in which:

Figure 1 is a perspective view of my improved crutch; Fig. 2 is a side elevation of 20 the upper end of the crutch, partly in section; Fig. 3 is an edge view of the crutch; and, Fig. 4 is a detail perspective view of the spring.

Corresponding and like parts are referred 25 to in the following description and indicated in all the views of the drawing by the same reference characters.

The body of the crutch is composed of the opposed bowed rods 2 held apart at their 30 middles by the handle 2^a, as is usual in crutches, the upper ends of the rods 2 being connected and spaced apart by the cross bar 3.

44 Fig. 4 designates the head of the crutch, having the usual somewhat crescent-shaped 45 form, the under face of the head being flat. Interposed between the under face of the head and the upper face of the cross bar 3 is a Z-shaped spring comprising the opposed 50 parallel attaching ends 5 which contact respectively with the under face of the head and with the upper face of the cross bar 3.

and the inclined portion 6 which connects with the opposite ends of the flat attaching portions 5. It will be seen that this Z- 55 shaped spring will flex at the point 7. The attaching ends or portions 5 are held to the head and cross bar respectively by screws 8 or in any other convenient manner.

It will be seen that a crutch having the head 60 supported thereon in the manner above described, provides not only for an upward and downward movement of the head to permit the crutch to shorten as it reaches a vertical position, but that it also provides for the 65 crutch head taking various angular positions with relation to the axis of the body of the crutch, in accordance with the movements of the shoulder and arm of the user, and that the head and body of the crutch have relative 70 movement with regard to each other, thus decreasing frictional contact between the upper face of the crutch head and the armpit of the user. It will be further seen that one end or the other of the crutch head may be 75 depressed so that the crutch head may take various angles, without affecting the angular position of the body of the crutch, but that the wide, flattened, Z-shaped spring 80 will prevent to a large extent any lateral 85 movement of the crutch head relative to the body of the crutch. This is most important, for the reason that any lateral movement of the crutch head would detract from the certain support of the crutch. 85

Our invention is simple, cheap, may be easily applied to crutches with a minimum of change therein, and makes a crutch which is very much easier for the user than a crutch having a solid head. 90

Having thus described the invention, what is claimed as new is:—

1. A crutch having a body or staff, a cross bar at the upper end of the body, a head separated therefrom, and a spring interposed 95 between the body and head, said spring extending diagonally from one end of the crutch head to the opposite edge of the cross bar.

2. A crutch having a body, a cross bar at the upper end of the body, a head, and a Z-shaped spring interposed between the body and cross bar, the parallel ends of said spring being attached to the under side 100

of the head and to the upper side of the cross bar respectively.

3. A crutch having a body, a cross bar at its upper end, a head, and a flat spring extending in a plane transverse to the length of the crutch and interposed between the head and body.

In testimony whereof we affix our signatures in presence of two witnesses.

CHESTER L. JENSEN. [L. S.]
LONNIE A. LAHEY. [L. S.]
